UNITED STATES PATENT OFFICE.

JOHN ELDRIDGE, OF WINNIPEG, MANITOBA, CANADA, ASSIGNOR OF ONE-HALF TO
HENRY BUTLER, OF WINNIPEG, MANITOBA, CANADA.

SHOE FASTENER.

1,425,245.

Specification of Letters Patent. Patented Aug. 8, 1922.

Application filed December 3, 1920. Serial No. 428,026.

To all whom it may concern:

Be it known that I, JOHN ELDRIDGE, of the city of Winnipeg, in the Province of Manitoba, Canada, have invented certain new and useful Improvements in Shoe Fasteners, of which the following is the specification.

The invention relates to improvements in shoe fasteners and the object of the invention is to provide a simply constructed inexpensive and durable device which can be readily attached to a shoe or boot and which is adapted to fasten the boot and dispense entirely with the customary laces at present employed.

A further object is to construct the device from metal and to arrange it so that it can be made from as few parts as possible and with the parts, with the exception of the spring latch, designed so that they can be stamped out in blank and afterwards folded to the proper shape.

A further object is to arrange the device so that where a number of them are employed as is required in fastening a boot the spring latches employed can all be released together thereby making it a very simple operation for one to undo the shoe or boot.

With the above more important objects in view the invention consists essentially in a receiving guide plate embodying fastening means, a spring latch carried by the guide plate and a catch adapted to be caught in the guide plate by the latch and provided also with fastening means, the parts being arranged and constructed as herein-after more particularly described, reference being had to the accompanying drawing in which:—

Fig. 1 represents a plan view of the toe of a shoe showing my fastening means employed to fasten the shoe.

Fig. 2 is an enlarged detailed plan view of the device removed from the shoe.

Fig. 3 is a perspective view of the catch.

Fig. 4 is a perspective view of the guide plate and latch.

In the drawing like characters of reference indicate corresponding parts in the several figures.

1 is a boot or shoe fitted at the front with the customary pairs of eyelet openings 2 and 3. Customarily the shoe or boot is closed by lacing through the eyelet holes. According to my invention, however, I provide the

fastening appliance now described it being understood that several of these are used and that in actual practice there would be probably fewer pairs of eyelet openings provided on the shoe than is required where it is closed by lacing. The fastener is now described in detail.

4 is a guide plate fitted at one end with a pair of inturned L-shaped guide flanges 5 and 6 and centrally with a pair of upturned comparatively long tongues 7 and 8 which have the upper parts brought together as indicated best in Figure 4 and their lower parts spread and elevated above the body of the plate to provide a guide opening 9 in line with the guide opening 10 beneath the flanges.

The tongues are designed so that they can be readily passed through the customary eyelet openings of the shoe. The plate is also provided with side wings 11 and 11' which are formed into sleeves receiving a wire 12 which has one end formed into an eye 13 and the extremity of the wire at the eye extended in a position at right angles to the wire body and forming a locking dog 14. The dog extends slidably through a suitable opening 15 provided in the side of the flange 6.

In order to positively secure the wire in place the end of the plate is cut and the material thereof is pressed upwardly and downwardly to provide a sleeve like fastening 16 at the end of the plate which is tightly pressed to clamp the wire. The wire forms in reality a locking latch adapted to fasten the catch now described.

17 is a catch in the form of a narrow plate adapted to pass into the grooves 9 and 10 and having one side fitted with teeth 18. The plate is also provided with two upwardly extending tongues 19 and 20 similar to those 7 and 8, and which are adapted to pass through the customary eyelet openings provided in the shoe. When this appliance is to be used on a shoe a number of them are taken and the tongues 7 and 8 and those 19 and 20 are passed through the pairs of eyelets of the shoe. The upper ends of the tongues are then flattened down to securely hold the guide plate and the catch in place. When this has been done one fastens his shoe by inserting the free end of the catch 17 into the grooves 9 and 10 and then by squeezing the two parts towards one another

he firmly tightens the front of the shoe and the catch is locked to the plate by the end 14 of the latch which rides over and engages the teeth.

- 5 In order to allow one to quickly undo the shoe I have connected the eyes 13 of the latches by a pulling string 21 which terminates at the top of the shoe. Obviously one by pulling the string 21 will simultaneously 10 withdraw all the dogs 14 and in so doing will release the catches and permit of the shoe being opened.

From the above it will be apparent that this provides a very quick, simple and efficient device for fastening shoes in the place of laces and that the various parts, with the exception of the latch, are so arranged that they can be quickly stamped from blank sheets of metal, the whole device embodying 15 only three parts in its construction, and all of which can be cheaply made and quickly 20 put together.

What I claim as my invention is:—

In a shoe fastener a guide plate presenting a pair of opposing guide flanges and a 25 pair of fastening tongues adapted to fasten the plate to one side of the shoe, a spring latch attached to the plate and provided with a dog operating through one of the guide flanges, an eye adjacent to the dog, 30 and a toothed catch adapted to be received between the guide flanges and with the dog engaging the teeth, said catch being fitted with fastening tongues adapted to fasten the catch to the other side of the shoe and a pulling string attached to the eye.

Signed at the city of Winnipeg, in the Province of Manitoba, this 13th day of August, A. D., 1920.

JOHN ELDRIDGE.

In the presence of—

GERALD S. ROXBAUGH,
K. B. WAKEFIELD.
